UNITED STATES PATENT OFFICE.

WILLIAM L. LUKENS, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

FUSE FOR PROJECTILES.

Application filed December 17, 1921. Serial No. 523,049.

To all whom it may concern:

Be it known that I, WILLIAM L. LUKENS, a citizen of the United States, and residing at Bethlehem, Northampton County, State 5 of Pennsylvania, have invented certain new and useful Improvements in Fuses for Projectiles, of which the following is a specification.

This invention relates to improvements 10 in fuses for projectiles and its object is to provide a fuse in which the detonating charge is carried by a movable part of the fuse and normally held out of register with the transmission train or in such position that 15 it will not be exploded in case of accidental ignition of the transmission, such detonating charge being automatically movable into position to be exploded by the transmission train when the projectile is fired. The term 20 transmission train as herein used will be understood to comprise delay trains and flash transmission trains.

In the drawings accompanying this specification and forming a part thereof; 25 Figure 1 is a section through the axis of the fuse showing the parts in armed position, that is, with the detonator in position to be ignited by the transmission train, the particular term illustrated being a delay train. 30 Figure 2 is a section on the line 2—2 of Figure 1 looking forward in the direction of the arrows;

Figure 3 is a similar section showing the detonator carrying block in unarmed position, that is, out of line or register with the delay train;

Figure 4 is a detailed section on the line 4—4 of Figure 2; and

Figure 5 is a detailed section on line 5—5 40 of Figure 3.

Referring to the drawings in detail 10 indicates a fuse stock which, as shown, is threaded at 10^a and adapted to be screwed into a threaded opening in the base of a 45 projectile.

The fuse stock is provided with a central cavity in which is mounted various parts to be hereinafter described. In the front part of the stock there is a chamber 11 which 50 is adapted to receive a booster charge, the chamber 11 being separated from the cavity heretofore mentioned by a partition 12 provided with an opening 13 through which the booster charge is detonated. As shown

the opening 13 is in the axial center of the 55 stock.

In the base of the fuse stock there is a movable plunger 14 carrying a firing pin 15. The plunger may be of any approved type adapted to move forward on impact 60 of the projectile and cause the firing pin to detonate the primer heretofore mentioned. The plunger is normally held in a rearward position by a restraining spring 18. Although the firing pin 15 is shown in the 65 drawings in its armed position, it will be understood that it is normally disarmed. Any well known means may be used to cause the firing pin to move from its disarmed to armed position on firing of the projectile, 70 for example the arrangement disclosed in the Patent No. 1,397,855, dated November 22, 1921. As shown, the plunger housing consists of a cylindrical block 17 provided with a threaded flange 18 for engaging similar threads on the stock. The front end of the plunger housing is formed by a plate 19, the restraining spring 16 being arranged between this plate and a shoulder on the 75 plunger.

A member 20 is fixedly mounted in the cavity of the fuse stock in front of the cylindrical block 17 and said member 20 has a central cavity in which a smaller block or member 21 is rigidly secured, the member 21 being arranged in front of the plate 19 heretofore mentioned. The member or block 21 is provided with a circuitous passage or channel 22 for receiving a delay train, this passage being formed in any 80 suitable manner. As shown it is produced by boring lateral and longitudinal channels in the member 21, the ends of which channels are closed by suitable plugs 23. The member 20 is provided with a channel or 85 recess 22^a which forms a continuation of the channel 22 in the member 21.

The plate 19 in line with the firing pin 15 is provided with an opening 24 which is adapted to receive a primer 25. The opening 24 communicates with the passage 22 heretofore mentioned. An opening 26 is provided centrally of the member 20 which opening communicates with a portion 22^a of the channel 22.

A detonator carrying block 27 is pivotally mounted in front of the member 20, this block being eccentrically arranged in

the cavity of the fuse stock and mounted on a pivot pin 28 secured in the partition 12 of the stock. The block 27 normally occupies the position shown in Figure 3 with its free end against a pin 29 mounted in the partition 12. It is held in this position yieldingly by a plunger 30 which is carried by the detonator block and pressed by a spring 31 against the wall of the cavity of the fuse stock. The block 27 is further held in the position shown in Figure 3 by a spring pressed locking pin 32 which bears against the partition 12 as shown in Figure 5, the pin 32 being adapted to enter a recess 33 in the partition 12 as illustrated in Figure 4 and lock the block 27 in the position shown in Figure 2. The block 27 carries a detonator or detonator charge 34. When the block 27 is in its normal or unarmed position, shown in Figure 3, the detonator 34 is held out of line or register with the opening 13 in the partition 12 and the opening 26 in the member 20. When the block 27 is moved to the armed position as shown in Figure 2 it will be understood that the detonator charge 34 occupies the position shown in Figure 1 of the drawing, that is, at such time the detonator charge will be in line or register with the delay train 22, 22^a and the opening 13 communicating with the booster charge in the chamber 11.

It will be understood that when the parts are in the unarmed position shown in Figure 3 accidental ignition of the transmission train by the primer 25 will not explode the detonator 34 because the detonator is not in register with the transmission train passage. When the projectile is fired from the gun the rotation of the same will cause the block 27 to move by centrifugal force into the armed position shown in Figures 1 and 2 and the block will then be locked in that position. The detonator 34 as heretofore stated is then in line with the delay train and with the opening 13 leading to the booster charge. When movement of the projectile is arrested as by means of impact with an object, the plunger 14 will be driven forward against the primer, the delay train will be ignited and the detonator charge exploded which in turn will explode the booster charge in the chamber 11. The booster charge, as is well known, ignites the bursting charge of the projectile.

The detonator block 27 may obviously be shaped in various ways but the form shown in the drawings is preferred. It will be noted that in this form one side of the block is arc-shaped and of the same radius as the cavity of the fuse stock. This formation gives the detonator block a large bearing surface to resist impact when the block is thrown to the position shown in Figure 1 as the projectile leaves the gun.

Having thus described the invention what I claim as new and desire to secure by Letters Patent is:

1. In a fuse for projectiles, the combination with a fuse stock and a plunger provided with a firing pin, of a transmission train arranged in said stock and having at one end a primer seat in line with said firing pin, an eccentric member pivotally mounted in said stock about an axis which is eccentric to and parallel with the axis of said stock, said eccentric member being disposed in front of said transmission train, a detonator carried by the eccentric member, and means for normally holding said eccentric member in position to maintain the detonator out of registry with the transmission train and the mass of said member being effective under the influence of centrifugal force due to rotation of the projectile to bring the detonator into registry with said transmission train.

2. In a fuse for projectiles, the combination with a fuse stock having a cavity and plunger located in the rear of the cavity and provided with a firing pin, of a member fixedly mounted in said cavity in front of said plunger and having a transmission passage extending from the rear to the front thereof, a primer seat arranged at the rear end of said passage in line with said pin, an eccentric member pivotally mounted in said cavity in front of said fixed member and about an axis which is eccentric to and parallel with the axis of the fuse stock, a detonator carried by said member, and means for biasing said member to a position to maintain said detonator out of line with the front end of said transmission train passage, the mass of said eccentric member being effective under the influence of centrifugal force due to rotation of the projectile to move the member in order to bring the detonator into line with said passage.

3. In a fuse for projectiles, in combination, a fuse stock having a chamber adapted to receive a booster charge and also having a cavity, said chamber having an opening communicating with said cavity, an eccentric member pivotally mounted in the front part of said cavity about an axis which is eccentric to and parallel with the axis of the fuse stock, a detonator for the booster charge carried by said eccentric member, a member fixedly mounted in said cavity at the rear of said eccentric member and having a transmission passage extending therethrough from the rear to the front thereof, means for yieldingly holding said eccentric member in position to normally maintain said detonator out of line with said opening and with the front end of said transmission train passage and the mass of said eccentric member being effective under the influence of centrifugal force due to rotation of the projectile to move the member in order to bring the detonator into line with said passage.

tion of the projectile to cause said eccentric member to move about its axis to bring the detonator into registry with said opening and passage, and means to ignite the transmission train in said passage when movement of the projectile is suddenly arrested.

4. In a fuse for projectiles, the combination with a fuse stock having a cavity, of an eccentric member pivotally mounted in the cavity about an axis which is eccentric to and parallel with the axis of the fuse stock, a detonator carried by the eccentric member, said fuse stock having a transmission train passage fixedly arranged therein, means for normally holding the eccentric member in unarmed position and the mass thereof being effective under the influence of centrifugal force due to rotation of the projectile to bring the detonator into registry with said transmission train passage, and means for igniting the transmission train in said passage when movement of the projectile is suddenly arrested.

5. In a fuse for projectiles, the combination with a fuse stock having a cavity, of an eccentric member pivotally mounted therein about an axis which is eccentric to and parallel with the axis of the fuse stock, a detonator carried by the eccentric member, means fixedly mounted in said stock and having a passage for receiving a transmission train, means for normally holding said eccentric member in unarmed position and the mass thereof being effective under the influence of centrifugal force due to rotation of the projectile to bring the detonator into registry with said transmission train passage, means for locking said eccentric member in the last-named position, and means for igniting the transmission train in said passage when movement of the projectile is suddenly arrested.

6. In a fuse, the combination of a fuse body having a booster charge and a transmission train therein, the booster charge and the transmission train having opposed and spaced terminal portions, a movable detonator adapted to be brought into alignment with said opposed terminal portions, a primer for the other terminal portion of the transmission train, and a striking pin for the primer.

7. In a fuse, the combination of a fuse body having a booster charge at its forward end and a transmission train arranged intermediate thereof, the booster charge and the transmission train having opposed and spaced terminal portions, a member movable transversely of the axis of the fuse body under the influence of centrifugal force due to rotation of the projectile, a detonator carried by said member and adapted to be brought into registration with the opposed terminal portions of the booster charge and

of the transmission train when said member has moved to its limit under the influence of centrifugal force, a primer at the other terminal portion of the transmission train, a plunger disposed rearwardly of the transmission train, a plunger disposed rearwardly of the transmission train and capable of moving axially of the fuse body, and a firing pin carried by the forward end of the plunger and adapted to ignite the primer upon retardation of the projectile to a predetermined extent.

8. In a fuse, the combination of a fuse body having a booster charge at one end portion and an intermediate transmission train charge, the booster charge and the transmission train charge having opposed and spaced terminal portions, a member movable between the terminal portions and adapted to be interposed therebetween in all positions thereof, a detonator carried by the member and adapted to be brought into alignment with said terminal portions in one position of said member, means for biasing the member in a direction to hold the detonator out of registration with said opposed terminal portions and said member being responsive to centrifugal force due to rotation of the projectile to bring the detonator into registration with said terminal portions, means for locking said member against movement when the detonator is in registering position, a primer for the other terminal portion of the transmission train charge, a plunger disposed rearwardly of the transmission train charge and capable of axial movement with respect to the fuse body, and a firing pin carried by the forward end of the plunger, whereby, upon impact of the projectile, the plunger moves forwardly to impinge the firing pin against the primer.

9. In a fuse, the combination of a fuse body having booster and transmission train charges with opposed and spaced terminal portions, a member movable transversely of the fuse body and normally separating the terminal portions, a detonator carried by the member and adapted to be brought into registration with the opposed terminal portions of said charges upon movement of said member in one direction, a primer for the other terminal portion of the transmission train charge, a plunger movable axially of the fuse body, a firing pin carried by the plunger and adapted to impinge with the primer upon axial movement of the plunger to a predetermined extent in one direction, and resilient means cooperating with the plunger and serving to resist movement of the firing pin toward the primer.

In testimony whereof I hereunto affix my signature.

WILLIAM L. LUKENS.
